[57] CLAIM

The ornamental design for a beverage can top, as shown and described.

DESCRIPTION

FIG. 1 is an exploded perspective view of a can and cooler in broken lines and a beverage can top showing my new design;

FIG. 2 is an enlarged front perspective view thereof;

FIG. 3 is an enlarged front elevational view thereof;

FIG. 4 is an enlarged left side elevational view thereof, the right side being a mirror image;

FIG. 5 is an enlarged top plan view thereof;

FIG. 6 is an enlarged bottom plan view thereof;

FIG. 7 is an enlarged front perspective view of a second embodiment of FIG. 1;

FIG. 8 is an enlarged front elevational view of FIG. 7;

FIG. 9 is an enlarged left side elevational view of FIG. 7, the right side being a mirror image;

FIG. 10 is an enlarged top plan view of FIG. 7;

FIG. 11 is an enlarged bottom plan view of FIG. 7;

FIG. 12 is an enlarged top front perspective view of a third embodiment of FIG. 1;

FIG. 13 is an enlarged front elevational view of FIG. 12;

FIG. 14 is an enlarged right side elevational view of FIG. 12, the left side being a mirror image;

FIG. 15 is an enlarged top plan view of FIG. 12; and,

FIG. 16 is an enlarged bottom plan view of FIG. 12.
